UNITED STATES PATENT OFFICE.

FRANK R. MCBERTY, OF EVANSTON, AND FREDERICK H. LOVERIDGE, OF CHICAGO, ILLINOIS, ASSIGNORS TO THE WESTERN ELECTRIC COMPANY, OF CHICAGO, ILLINOIS, A CORPORATION OF ILLINOIS.

MACHINE FOR SEALING INCANDESCENT LAMPS.

SPECIFICATION forming part of Letters Patent No. 734,734, dated July 28, 1903.

Application filed November 5, 1900. Serial No. 35,540. (No model.)

To all whom it may concern:

Be it known that we, FRANK R. MCBERTY, residing at Evanston, and FREDERICK H. LOVERIDGE, residing at Chicago, Cook county, Illinois, citizens of the United States, have invented a certain new and useful Improvement in Machines for Sealing Incandescent Lamps, (Cases Nos. 92 and 20,) of which the following is a full, clear, concise, and exact description.

Our invention relates to the manufacture of incandescent electric lamps of the kind at present in extensive use as signal-indicators for telephone-switchboards. In the manufacture of such lamps a hollow glass stem is enlarged or expanded at a point a short distance from its tip and the two platinum "leading-in" wires which carry the carbonized filament are attached to the tip of the stem and extend downward on the outside thereof past the expanded portion. A cap or bulb substantially of the diameter of the expanded portion of the stem is then fitted down over the stem until the lower edge of the cap embraces the expanded portion, whereupon heat is applied at this point to fuse the cap and stem together and seal in the wires. In order that the two parts may be properly welded together, it is necessary to blow air into the hollow stem while the parts are heated, so that the enlarged portion of the stem will expand still further and press itself firmly onto the inclosing cap. After the lamp is formed, as above described, the hollow stem may be attached to an air-pump and the air exhausted in the usual way.

The object of this invention is to produce a machine for performing quickly and accurately the operation of sealing the cap to the stem, whereby the incandescent lamps may be manufactured in larger quantities with very little labor or expense. The machine which we have constructed for this purpose will be described particularly by reference to the accompanying drawings, and that which we regard as new will be pointed out in the appended claims.

Figure 1 is a side elevation of the machine. Fig. 2 is a front view thereof. Fig. 3 shows the cap and stem which go to make up an in-

candescent lamp. Fig. 4 shows these parts united to form the complete lamp as accomplished by the machine illustrated. Fig. 5 is a front vertical sectional view on line 5-5 of Fig. 1. Fig. 6 is a similar view on line 6-6. Fig. 7 is a plan view showing the manner in which a large number of caps are manipulated by the machine to bring one after another into position to be fused upon the lamp-stem, and Fig. 8 is a detail view of a mandrel which we employ to support the hollow glass stem while the cap is being sealed on.

Similar letters of reference are used to designate the same parts wherever they are shown.

Referring first to Figs. 3 and 4, the hollow glass stem *a* is expanded or enlarged at *a'* a short distance below the tip. The two platinum leading-in wires *a²* *a³*, which carry the carbonized filament *a⁸*, are attached to the stem at the tip and extend down the side thereof, resting upon the enlargement *a'*. The cap *b* is cylindrical, the end being rounded, as shown. The inner diameter of this cap is substantially the same as the diameter of the enlargement or expanded portion *a'* of the stem. In order to form the incandescent lamp, the cap *b* is fitted down over the stem *a* until the lower edge of the cap embraces the enlargement *a'*, whereupon the parts are heated until they fuse together at this point, as shown in Fig. 4, air being blown through the hollow stem to expand the portion *a'* thereof sufficiently so that a good weld will be formed. In the machine shown in the drawings for manipulating these glass parts and welding them together a rotatable chuck *c* is provided for holding the cap *b*, said chuck being movable in a vertical plane, and a second chuck *d*, rotating at the same speed as the other, is adapted to hold the stem *a*. This lower chuck *d* preferably has no vertical movement. Two glass-blowers' fires *e* *e* are disposed one on either side of the lower chuck and adjusted to direct their flames upon the line where the cap and stem touch each other. The upper chuck *c* consists of spring-jaws *c'* *c''*, carried upon the lower end of a tube *c²* which is contained within a tubular shaft *c³*.

The shaft c^3 is journaled to rotate in a head or stock f , which is bolted upon the upper portion of the standard g of the machine. The shaft c^3 is mounted to rotate with but is longitudinally movable relatively to a gear-wheel c^4 , which is mounted at the lower end of the head f , said gear-wheel being driven through an intermediate idler-gear h^2 by a gear h' , carried upon the vertical driving-shaft h . The shaft c^3 has a slot c^6 cut through its walls near its upper end, and through this slot a pin c^7 is passed from a ring c^8 , inclosing said shaft into the tube c^2 . The ring c^8 is longitudinally movable upon the shaft c^3 , the pin c^7 being adapted to slide up and down within the slot c^6 . The shaft c^3 also carries a ring c^9 , rigidly fixed thereto, and a helical compression-spring c^{10} encircles the shaft between the rings c^9 and c^8 , tending to raise the inner tube c^2 as far as the play allowed the pin c^7 within the slot c^6 will permit. When the inner tube c^2 is retracted within the shaft c^3 , as shown in Fig. 5, it will be seen that the jaws $c' c'$ of the tube forming the clutch will be forced together. The clutch, in other words, is normally kept tightened by the spring c^{10} , but is loosened when the ring c^8 , which is attached to the tube c^2 , is moved downward toward the ring c^9 against the tension of the helical spring c^{10} . The shaft c^3 is longitudinally movable within the head f , the downward movement of the shaft being limited by the engagement of the ring c^9 with an abutment or shoulder f' , formed in the head, and the upward movement of the shaft being limited by the ring c^8 striking against a stop or abutment f^2 , formed in the upper portion of the framework. When the shaft c^3 has ascended sufficiently for the ring c^8 to strike this stop f^2 , the upward movement of the shaft may be continued against the tension of the spring c^{10} for a short distance until that portion of the shaft at the lower edge of the slot c^6 strikes the pin c^7 , attached to the tube c^2 . When the shaft is thus raised as high as it will go, the clutch c' is opened, since the pressure of the lower edge of said shaft upon the sloping spring-jaws c' is removed and the jaws spring outward.

The lower chuck for holding the glass lamp-stems is made in a different way from the upper chuck c . This lower chuck is rotatable within the stock or head k and is driven, by a set of gear-wheels, from the driving-shaft h in the same manner as the upper chuck; but, unlike the upper chuck, it has no vertical movement. This lower chuck d has a hole in its upper portion just large enough to permit the lamp-stem a to be inserted therein.

The interior of the chuck contains an annular piece of soft sponge-rubber d' , and when the lamp-stem is inserted in the chuck the lower end of the lamp-stem is pushed into the soft-rubber annulus until the expanded portion a' of the stem rests upon the tip of the chuck.

Means are provided, which will presently

be described, for admitting air to the interior of the chuck, and the annulus of soft rubber prevents the passage of air through the chuck except through the bore of the tubular lamp-stem. The lower portion d^2 of the chuck has a bore communicating with the upper portion thereof, which contains the soft-rubber annulus, and a stationary cylindrical tube d^3 , which is connected with a source of air-supply, fits closely into the bore of the lower portion of the chuck. This tube, while not revolving with the body of the chuck, is made to fit so closely within the bore thereof that it makes an air-tight joint, whereby air from the supply-tube l may be communicated to the interior of the chuck and thence to the hollow lamp-stem, which may be inserted therein.

In order that a good weld may be made between the lamp-cap and the stem, it is necessary that the glass be heated to such a degree that it will flow easily, and in order to prevent the lamp-stem from collapsing when so heated we provide a mandrel m in the interior of the chuck, over which the lamp-stem is fitted when it is inserted into the chuck, the mandrel passing into the bore of the stem. This mandrel is provided with grooves in its sides—that is to say, it is not cylindrical in cross-section, but star-shaped—so that air may be passed through the lamp-stem, by way of the grooves in the mandrel, without impairing the efficiency of the mandrel as a support for the stem. A bracket k' is attached to the stop or head k , and the tube d^3 is mounted upon this bracket, being secured thereto by a thumb-screw d^4 . The mandrel m is screwed into the body of the chuck and may be inserted or removed at any time from underneath by first loosening the thumb-screw d^4 and removing the tube d^3 . A pair of jaws $l' l'$ are provided, which are adapted to grasp the soft-rubber air-supply pipe l and flatten it together to cut off the flow of air. These jaws $l' l'$ may be grasped by the operator and opened to any extent necessary, thus controlling the amount of air admitted to the chuck. A rocking arm n is pivotally connected, by a link n' , with the upper part of the standard g or framework of the machine. The forward end of this lever carries pins $n^2 n^2$, which engage with an annular channel c^{11} , provided in the upper portion of the tubular shaft c^3 . Said shaft c^3 , while free to rotate, may thus be moved longitudinally up and down within the head f by means of the rocking lever n . Said rocking lever is connected, by means of a link n^3 , with an operating-lever o , pivoted at o' to the lower portion of the framework of the machine. The shaft c^3 , which carries the clutch c , may thus be raised and lowered at will by raising and lowering the operating-lever o .

The driving-shaft h , by which the two chucks c and d are rotated at the same speed, is connected, by means of a clutch h^3 , with a driving-wheel h^4 , to which power is applied

by means of a driving-belt. The clutch h^3 is controlled by means of the treadle h^5 , whereby the rotation of the chucks may be started or stopped at will.

5 In the operation of the machine the lamp-stems a are placed in the chuck d by hand; but we have provided means whereby a large number of lamp-caps may be fed automatically into the upper chuck c without any manual adjustment by the operator. We will now proceed to describe this automatic feeding mechanism. A circular magazine p , having a number of notches $p' p'$ in its periphery, is mounted to rotate in a horizontal plane at the top of the machine, said magazine having a number of vertical holes near its periphery, which are adapted to contain the lamp-caps, as shown in Figs. 1, 2, 5, and 7. The holes in the magazine are sufficiently large so that the lamp-caps may move freely therein; but a circular glass plate p^3 is provided immediately below the magazine, upon the upper surface of which the lamp-caps slide as the magazine is rotated, so that the lamp-caps are kept from falling out. The glass plate p^3 is supported by an iron plate p^4 of a strength suitable to support the weight. A vertical tubular guide q is mounted in the framework of the machine immediately over the bore of the tube c^2 . The upper end of this guide opens immediately below a hole in the circular glass plate p^3 and its metallic support p^4 . When the magazine is rotated so that one of the caps is directly over this tubular guide q , it will be seen that the cap will fall through the hole in the glass plate and its support and thence through the tubular guide and into the tubular chuck c^2 , ending in the jaws $c' c'$. On the under side 40 of the magazine p there is provided a ratchet-wheel p^5 , having the same number of teeth as there are holes for caps in the magazine. A pawl p^6 is mounted upon a bracket p^7 , attached to the framework of the machine. A lug n^4 is provided on the rocking arm n , which is adapted when the arm is raised to strike the pawl p^6 and cause the same to engage the ratchet p^5 , whereby the pawl advances the ratchet-wheel through an arc equal to the 45 distance from one tooth of the ratchet to another. A spring-actuated trigger r engages the notches $p' p'$ in the periphery of the magazine p and prevents the magazine from rotating except when it is advanced by the pawl 50 and ratchet. A finger n^5 is carried by the arm n and engages the trigger r just before the lug n^4 strikes the pawl p^6 , so that the trigger r is moved clear of the notch in the periphery of the magazine and permits the magazine to be 55 rotated. A swinging platform or stop s is provided for supporting the caps as they are fed into the upper chuck before said chuck is tightened. Said platform s is carried upon the lower end of the vertical shaft s' , which is mounted in bearings s^2 , so as to be capable of a rotary reciprocating motion. The upper end of said shaft s is bent outward to form a

crank and connected to a horizontal sliding rod s^3 , which is adapted to be reciprocated by a bell-crank lever s^4 , pivoted at s^5 to the framework of the machine. One end of said bell-crank lever engages and moves the rod s^3 , while the other or horizontal arm thereof is pivoted to the lower end of a vertical reciprocating rod s^6 , which extends upward through a hole in the operating-lever n and carries at its upper end a nut s^7 , which is adapted to be engaged by the operating-lever when the latter is moved to its highest position. A spring s^8 normally holds the bell-crank lever down in the position shown in Fig. 1, so that the rod s^3 will occupy its rearward position and the vertical shaft s' will be maintained in a position such that the platform s will be clear of the chuck. When 85 the lever n is moved up, however, it engages the nut s^7 , carried by the vertical reciprocating rod s^6 , so that the bell-crank lever s^4 is rotated about its pivot s^5 , and through the agency of the rod s^3 the vertical shaft s' is 90 also rotated and the platform s is swung under the lower end of the shaft c^3 just as the said shaft reaches the end of its upward journey and an instant before the magazine drops one of the caps into the tubular chuck. The 95 platform s thus serves to support the cap which has fallen into the chuck before said chuck is tightened. Upon the descent of the arm n after it has moved sufficiently to tighten the chuck, but before the shaft c^3 100 has made any downward movement, the vertical rod s^6 will be retracted through the agency of the spring s^8 sufficiently, so that through the intermediate lever mechanism the shaft s' and the platform s , carried thereby, will be rotated so that the platform will 105 be swung to one side clear of the chuck to permit the descent of said chuck without interference. A swinging tray t is also provided, which is adapted to be moved underneath the upper chuck c just as said chuck is loosened at the upper end of its journey, so that the lamp released from the chuck 110 will fall into the tray. Mechanism is provided to swing the tray out again as the chuck 115 descends and to dump the lamp from the tray into a box.

In the operation of the machine the magazine is first filled with caps, as shown in Figs. 1 and 2, and a lamp-stem having the filament attached thereto is inserted by hand in the lower chuck d , being fitted down over the mandrel m until the bulb or enlarged portion a' of the stem rests upon the upper surface of the chuck, in which position the lower end 120 of the stem will be encircled by the soft-rubber annulus d' . The operating-lever o is raised by hand to lift the upper chuck while the lamp-stem is being inserted in the lower chuck, and as the lever is raised the following movements take place: The tray t is 125 swung in under the upper chuck. The ring c^8 strikes against the stop f^2 , whereby as the shaft c^3 continues its upward movement the 130

chuck *c* is loosened. The finger *n*⁵ strikes the trigger *r* and releases the magazine, so that it is free to rotate. The lug *n*⁴ then strikes the pawl *p*⁶, which pawl then engages the ratchet and rotates the magazine, and just before the magazine is rotated sufficiently to bring one of the caps over the hole in the glass plate the swinging platform *s* is moved under the lower end of the tubular chuck. Then finally the cap which has been moved over the hole in the glass plate falls through the tubular guide *q* into the tubular chuck *c* until it is stopped by striking against the platform *s*, which has been moved under the chuck to support it. The platform *s* is provided with a spring mounting, so that the glass cap will be in no danger of breaking by the too sudden arresting of its fall. The operating-lever is now moved downward, and the first effect of this movement is to cause the clutch *c* to tighten upon the cap therein contained, as previously explained. As soon as the clutch has grasped the cap the platform *s* is swung to one side out of the downward path of the clutch. The trigger *r* has now again snapped into the notch *p'* of the magazine, which is opposite it, preventing backward or other movement of the magazine. The operator now by pressing upon the treadle *h*⁵ starts the two chucks to rotating together. When she has moved the operating-lever *o* downward far enough so that the cap *c* is fitted over the stem which is contained in the lower chuck, she starts the operation of the fires, the points of the flames being directed upon the ring of contact of the cap and stem, whereby the two parts are heated sufficiently to fuse together. Now by manipulating the jaws *l' l'*, which control the air-supply pipe *l*, she can admit air into the interior of the lower chuck until air passes up through the soft-rubber annulus and through the grooves in the mandrel *m* to the interior of the lamp-bulb which is being formed. This air-pressure expands the glass of the stem at the part *a'* and presses the stem and cap firmly together, so that a perfect weld or seal is formed. The stem during its heated condition is supported by the mandrel *m*, as previously described. As soon as the cap and stem have been thoroughly sealed together the supply of gas to the flames is cut down and the parts allowed to cool. When the newly-formed lamp has cooled sufficiently, the operating-lever *o* is raised, and as the upper chuck *c* ascends the stem *a* is pulled out of the lower chuck. When the chuck *c* arrives at the upper end of its journey, the tray *t* is moved under the chuck, which is loosened, as previously explained, and the lamp is dumped into the tray. When the operating-lever *o* is moved down the next time, the tray is swung out to the right of the machine and the lamp dumped out into a box or other receptacle waiting to receive it. A complete cycle in the operation of the machine has now been traced.

In case obstructions, such as broken glass

or dirt, should find their way into the lower chuck through the opening in the top thereof the tube *d*⁸ may be removed in a moment 70 by unscrewing the thumb-screw *d*⁴, whereupon the mandrel *m* may be unscrewed and taken out, the interior of the chuck being thus easily accessible. This feature is also useful in case the mandrel should need 75 repairing. It will be observed also that the lower portion *d*² of the lower chuck may be unscrewed, if desired, in order to obtain access to the inner chamber to renew or adjust the soft-rubber packing *d'*, contained therein. 80

Having thus described our invention, we claim as new, and desire to secure by Letters Patent, the following:

1. The combination with a chuck for holding a hollow glass stem, said chuck having a 85 hole for the insertion of the stem, and an interior chamber into which the hole leads, means for supplying air under pressure to said chamber, and an annular packing of soft or yielding material, as rubber, disposed 90 within said chamber at the mouth of the hole leading into the same, said annular packing being adapted to grasp and hold the inserted glass stem, and to prevent the air from escaping through said hole except through the 95 bore of said stem, as set forth.

2. The combination with a chuck *d* for holding a hollow glass stem, of a second chuck in alinement with the first, adapted to hold a glass cap, mechanism for bringing the chucks 100 nearer together to fit the cap upon the stem, mechanism for rotating the two chucks at the same speed, a fire for heating the cap and stem at their point of contact to seal them together, a source of air under pressure connected with the free end of the hollow stem, and a mandrel in the chuck which holds the stem, said mandrel extending into the bore of the stem to support the same, but being adapted to permit the passage of air through 105 the stem, substantially as set forth.

3. The combination with a chuck *d* having a bore adapted to hold a hollow glass stem, of a second chuck in alinement with the first, adapted to hold a glass cap, means for bringing the chucks together to fit the cap upon the stem, means for rotating the two chucks at the same speed, a fire for heating the cap and stem at their point of contact, to seal them together, and a mandrel in the first-mentioned chuck, extending through the bore of the chuck into the glass stem and adapted to support the stem while the same is softened by the heat, as set forth.

4. The combination with a vertical tubular 125 chuck, of a lever for raising and lowering the same, driven gears for rotating the chuck, a plate above the chuck having an opening over the bore thereof, a magazine having holes adapted to hold a number of glass caps in a 130 vertical position resting upon said plate, said magazine being movable to slide said caps along the plate and bring them one after another over the hole in said plate, through

which hole the caps may fall into the chuck, and a pawl operated by said lever for moving the magazine, as set forth.

5. The combination with a pair of chucks in vertical alinement, the lower chuck being adapted to hold a glass stem, and the upper chuck being adapted to hold a glass cap fed into said chuck from the upper end thereof, mechanism for rotating the chucks at the same speed, mechanism for bringing the chucks nearer together to fit the cap upon the stem, a fire for heating the cap and stem at their point of contact, to seal them together, a magazine at the top of the machine holding 15 a number of glass caps in a vertical position, and means for moving said magazine past the upper end of the tubular upper chuck, to drag the caps one after another into said chuck, substantially as set forth.
20. 6. The combination with a chuck *d* having

a hole adapted to receive a glass stem, a mandrel *m* adapted to be screwed into the interior of the chuck opposite the hole, extending up through the hole to form a support for the stem, but adapted to permit the passage of 25 air through the stem, means for rotating the chuck, a stationary cylindrical tube *d*³ connected with a source of air under pressure, said tube fitting closely into the rotatable chuck, and a removable support for the tube, 30 whereby the tube may be withdrawn from the chuck to permit access to the interior thereof, as set forth.

In witness whereof we hereunto subscribe our names this 10th day of October, A. D. 1900. 35
